CLAIM

The ornamental design for a computer stand with slid-

ing keyboard shelf, substantially as shown and described.

DESCRIPTION

FIG. 1 is a perspective view of the computer stand with sliding keyboard shelf showing our new design, the stand being in the closed condition;

FIG. 2 is a perspective view thereof, the front being in the open condition and the keyboard shelf being retracted;

FIG. 3 is a perspective view thereof, the shelf being fully extended;

FIG. 4 is a top plan view of the stand in the closed condition;

FIG. 5 is a bottom plan view thereof;

FIG. 6 is a front elevational view thereof;

FIG. 7 is a rear elevational view thereof;

FIGS. 8 and 9 are respectively left and right side elevational views thereof;

FIG. 10 is a top plan of the stand in the open condition with the shelf extended;

FIG. 11 is a bottom plan view thereof;

FIG. 12 is a front elevational view thereof;

FIG. 13 is a side elevational view thereof;

FIG. 14 is a front elevational view of a second embodiment of our new design, the stand being in the closed condition;

FIG. 15 is a rear elevational view thereof;

FIGS. 16 and 17 are respectively right and left side elevational views thereof;

FIG. 18 is a bottom plan view thereof;

FIG. 19 is a front elevational view of the stand of the second embodiment in the open condition;

FIG. 20 is a side elevational view thereof with the shelf extended;

FIG. 21 is a bottom plan view thereof;

FIG. 22 is a top plan view of the stand in the closed condition;

FIG. 23 is a top plan view of the stand in the open condition with the shelf extended.
